UNITED STATES PATENT OFFICE

GARABED G. HEGHINIAN, OF BALTIMORE, MARYLAND

MOLDING PRESS

Application filed August 28, 1926. Serial No. 132,240.

The main object is to provide a simple, powerful and reliable press for forming articles from moldable material.

Another object is to provide a construction of this character for molding alternately in a number of molds.

Another object is to provide for the automatic control of the molding pressure so as to produce uniform results and avoid injury to the machine.

Another object is to insure perfect molding, particularly around the edges of the article.

Another object is to insure automatic ejection of the articles.

The particular machine herein illustrated is designed for handling materials such as mixtures of asphalt, saw-dust and clay, or other mineral aggregate.

The machine illustrated constitutes one instrumentality in a process of forming blocks embodying new and useful characteristics. For instance, a block formed of asphalt, saw-dust and clay useful especially for road paving purposes. Such an article is made by mixing saw-dust with clay and water and then adding liquid asphalt and mixing the materials at a temperature sufficient to evaporate the water. The resultant substance is adapted to be molded under pressure and without the addition of further heat.

Figure 1 is a side view of one form of press embodying my invention.

Figure 2 is a front view of the same.

Figure 3 is a longitudinal sectional view of the machine.

Figure 4 is a transverse section of the machine.

Figure 4^a is a section of a modification.

Figure 5 is a rear elevation.

Figure 6 is a side view of an accumulator to be used with the press.

Figure 7 is a fragmentary vertical sectional view of a hopper and feed device.

Figure 8 is a plan view of one form of an anvil or bottom die.

Figure 9 is an end view of the same.

Figure 10 is a side view of the same.

Figure 11 is a longitudinal sectional view of the same.

Figure 12 is a plan view of the slide for

feeding the charges of material to the dies.

The frame of the press consists of three main parts, a base 15, which contains part of the hydraulic equalizing mechanism, and intermediate part 16 constituting a die body 55 and table, and the upper part 17 which carries the driving mechanism, crank shaft and plungers.

The die body is provided with two molding recesses 18 and 19. The anvil members 20 60 and 21 are adapted to move up and down in these recesses and form the lower die faces for the blocks to be molded. A rocker member has a shaft 22 resting in bearing 23 in the upper part of the base 15. This rocker member has two side arms 24 and 25 connected by cross bars 26 and 27 which are mounted in slots in the opposite ends, and which are loose in slots in the bottom of the anvil members 21 and 20 respectively. Two 70 pairs of push rods 28 and 29 are mounted on the ends of the cross rods 26 and 27 and guided in the upper part of the body 16, so that they can move up and down and transmit a corresponding action through the rocker 75 on the shaft 22.

The plungers 30 and 31 mounted above the anvil members 20 and 21, are adapted to be raised and lowered by the crank shaft 32 and the connecting rods 33 and 34 respectively 80 and alternately.

The driving of the crank shaft is effected from the gear 35 and shaft 36, which carries gear 37 meshing with gear 38. This latter is on the shaft 39, which carries gear 40 meshing with gear 41 on the end of the crank 85 shaft.

On the die body is mounted a slide 42 having openings 43 and 44 of the same horizontal cross sectional shape and size as the plungers 30 and 31, and recesses 18 and 19, and anvils 20 and 21 respectively. This slide is reciprocated on the die body by two arms 45, which are hinged to the center of the slide and to a lever 46 hinged at 47. The connection between the lever 46 and the rods 45 is effected by eye bolts and nuts so as to permit adjustment of the length of stroke and of the position of the slide on the die body.

One form of such construction consists of 100

an eye bolt 48 on the end of the bar 45 adjustable in position by the nuts 49 and 50 so as to move the slide 42 to the desired position for registration with the recess 18. The eye bolt 51 on the shank of eye bolt 48 is itself secured in a vertically adjusted position with respect to the lever 46 by the nuts 52 and 53. The two eye bolts 48 and 51 are connected by the coupling sleeve 54. The vertical adjustment of the eye bolts 51 changes the effective length of the lever 46 so as to vary the throw of the slide 42 so as to bring the opening 43 into registration with the recess 19. The lever 46 has a roller 55 at its upper end which extends into the groove of cam 56 on the end of the crank shaft 32 so that as the crank shaft rotates the lever 46 oscillates and reciprocates the slide 42 between the plungers and anvils.

The material to be molded is fed through a hopper or chute 57 to a point immediately above the slide 42 and midway between the recesses 18 and 19. To facilitate the operation, the chute has a horizontal portion 58 at its lower end in which is mounted a screw thread or propeller 59 on the shaft 60. This shaft has a stepped pulley 61 belted to the stepped pulley 62 on the shaft 63 which carries the spiral gear 64 which meshes with another spiral gear 65 on the shaft 39. These stepped pulleys make it possible to vary the rate of rotation of the conveyor screw 59 and hence vary the amount of material fed to the slide openings 43 and 44 so as to control the amount of the material for the desired thickness of blocks to be formed. The depth of the block or thickness may be regulated by putting in or taking out shim plates 89 above the pistons or rams.

It is thus possible to make blocks of different thicknesses with the same mechanism, by simply changing the speed of feed of the material and the shims on top of the pistons or rams.

The plungers are provided with projecting lugs 66 which extend out over the rods 28 and 29 respectively so that when one plunger, for instance, 31, is depressed it will at the lower end of its stroke, engage the rods 28, and push them down thus tilting the rocker about the shaft 22 and forcing upward the anvil 20 so as to eject the block from the recess 18 in the path of movement of the slide 42 which will, at this time, be at the right of the position shown in Figure 3.

The parts of the frame are secured together by bolts 70. To regulate and equalize the pressure, I prefer to provide hydraulic mechanism, including an accumulator cylinder 71 and plunger 72, and a suspended weight 73. In the bottom of the base 15 are two cylinders 74 and 75 connected by a pipe 76 to the accumulator cylinder. Pistons or rams 77 and 78 in these cylinders are provided with packing rings 79 and 80. These

pistons are held in place by locking plates 81 and 82. The weight 73 may be varied by adding or subtracting weights. Liquid may be pumped into the accumulator through the valve 83 and its pressure may be indicated by a gage 84.

Each anvil, such as 21 preferably has a central member 85 supported on springs 86 and held down by a cross piece 87 and pin 88.

In the operation of the machine, if we assume that the parts are initially in the position of Figure 3, the molding composition is fed through the chute 57 and forced by the screw 59 into the opening 43 in the slide 42. The cam 56 is so timed that the slide 42 is not moved until the plunger 30 has been entirely withdrawn from the opening 44. When the plunger is cleared, the slide is moved to bring the opening 43 and its charge over the anvil 21 and the prospective recess 19. The plunger 31 is then forced downward through the opening 43 and compresses the material in the recess 19. In this action the anvil 21 bottoms on the shim plate 89 on top of the piston or ram, 78. It will be seen, that the stroke of the reciprocating plungers 30 and 31, is positively determined by the design of the crank shaft and consequently the amount of compression of the block is determined by the pressure in the accumulator, that is, of course, assuming that there is a reasonably full charge of material in the opening 43 to begin with.

In case an excessive amount of material has been fed into the die it simply results in the production of a block of slightly greater thickness and without injury to the apparatus, since the anvil and piston can move downward equivalent to the excessive thickness by forcing the liquid in the cylinder back into the accumulator.

The blocks are ejected from the die by the positive action of the lugs 66 striking the rods 28 and rocking the ejector frame about its shaft 22 so as to lift the anvil 20 and push the block from the recess 18, out of the die into the path of movement of the slide 42 which pushes the blocks out of the way as the slide moves back and forth. Obviously, the ejection of the block from the recess 19 occurs in the same way when the plunger 30 moves downward and the block is forced from the recess 19 into the path of movement of the slide 42. Thus two blocks are formed at each revolution of the crank shaft 32. The form of anvil face shown in Figures 8 to 11 insures the production of a block which is perfect around the edges since the springs 86 hold up the center of the die while the material is fed into the die, thus insuring that more material fall all around the die than at the center.

The strength of the springs 86, however, is merely sufficient to hold up the central portion while the feeding of the die and the

initial pressure take place, after which the excessive pressure forces the central part 85 flush with the body of the anvil.

The ends of the member 87 engage the plate 16 on opposite edges of the recess 19 when the anvil is in the position shown at the right in Figure 3, so that the center piece is flush with the face of the anvil.

In the modification shown in Figure 4^a the plunger consists of two parts namely, the die part 90 supported on springs 91 and the ram 92 to which the connecting rod 93 is connected. This form has certain advantages over the first form but the first form of Figure 4 is more positive in its withdrawal action.

The slide 42 may have separable ends 42' connected by yieldable catches 42^a as shown in Figure 12 so that in case the plungers 20 stick in the die, the slide can separate or pull apart and thus prevent breakage.

One of the compositions or materials suitable for molding consists of from 40 to 50 parts by weight of saw-dust, from 50 to 40 parts of asphalt, and about 10 to 20 parts of clay. The clay is mixed with water so as to soften all lumps and nearly as possible form a colloidal solution. This is then added to the saw-dust in a double walled mixer and heated to about 200° F. while mixing, the saw-dust absorbs the water and clay. Hot liquid asphalt is then added and the mixing continued under a temperature of 300 to 500° F. for about 20 to 30 minutes or until the water is entirely evaporated, leaving the wood impregnated and coated with clay and the asphaltic substance. The material, when properly mixed, resembles the consistency of wet sand and is very easily handled and molded. Although saw-dust is preferred, some small wood chips or particles may be used. The pressure of molding is preferably from one to two tons per square inch. Although I prefer to use clay, it should be understood that other finely divided mineral substances may be used with or in place of the clay for some purposes.

In fact, roadside material including clay, dirt and fine sand, etc., can be mixed with water and asphalt and then the water evaporated so as to form asphalt impregnated durable road paving material.

The process of preserving wood may also be applied to wood blocks without vacuum or pressure so as to impregnate them with clay and water and then immerse in hot asphalt or creosote until the water is evaporated.

It should be understood also that the press may be used for molding asphaltic material containing crushed stone.

I claim:

1. A molding press comprising a die bed having a recess, a lower molding plunger relatively movable in said recess and formed

of at least two parts one of which has an upper molding surface which is normally below the upper molding surface of the other part so as to provide room for a greater depth of moldable material over one part than over the other part, an upper plunger 70 movable into said recess from above and spring means between the two parts of the lower plunger for allowing the molding surfaces of the two parts of the lower plunger 75 to move relative to each other.

2. A molding press comprising a die bed having two molding recesses, an anvil and a plunger to co-act in each recess, a rocker connecting the two anvils, a feeding slide having two passages, movable between said plungers and anvils, means for feeding the moldable material to a passage in said slide between said recesses and means for moving the slide to bring the filled passages alternately in registration with the respective plungers and anvils. 85

3. A molding press comprising a die bed having two molding recesses, anvils movable in said recesses, a rocker connecting said anvils, plungers to co-act with the anvils, a crank shaft for operating said plungers, means for feeding material alternately to said recesses and means for operating said rocker to alternately move said anvils to 90 eject the finished article. 95

4. In a molding press, a die member having two molding recesses, an anvil and a plunger movable in each recess, a slide movable on said die member between said plungers and anvils and having passages for the plungers, a rocker connecting the two anvils for feeding material alternately to said passages and means whereby when one plunger is acting to form a block in its respective die it moves the anvil co-acting with the other plunger and vice versa. 100 105

5. A molding press comprising two molding units, means for operating them alternately and hydraulic control and equalizing means co-acting with said units. 110

6. In a molding press, a die bed having a recess, a lower molding plunger movable in said recess and formed of at least two parts one of which has an upper molding surface which surrounds and is normally below the upper molding surface of the other part so as to provide room for a greater depth of moldable material around the edge than over the central part, an upper plunger movable into said recess from above and means for allowing the molding surfaces of the two parts of the lower plunger to approach a common level. 115 120

7. A molding press comprising a die bed having a recess, a lower molding plunger relatively movable in said recess from below and formed of two parts one of which surrounds the other and has an upper molding surface which is normally below the upper 125 130

5 molding surface of the other part, an upper compressing plunger relatively movable into said recess from above and spring means for allowing the molding surfaces of the two parts of the lower plunger to move relative to each other as the upper and lower plungers compress the material in the recess.

10 8. A molding press comprising a die bed having a recess open at the top, a lower molding plunger movable in said recess and formed of at least two parts one of which has an upper molding surface which is normally below the upper molding surface of the other part so as to provide room for a greater depth of moldable material over one part than over the other part, an upper compressing plunger movable into said recess from the top and means for allowing the molding surfaces of the two parts of the lower plunger to approach a common level as the upper and lower plungers compress the material in the recess.

15 9. In a molding press the combination of a die bed having a recess open above and below, upper and lower plungers relatively movable into said recess from above and from below said die bed, the lower plunger having two relatively movable parts one of which surrounds the other and at certain times has its upper molding surface held at a level different from the level of the inner part and means for moving the two parts of the lower plunger relative to each other.

20 10. In a molding press, a die bed having two passages, plungers mounted above and below each passage, means for alternately raising and lowering the upper plungers and the lower plungers comprising a rocker arm between the two lower plungers and means for alternately feeding material to the two passages.

25 11. In a molding press, a die bed having two passages, plungers mounted above and below each passage, means for alternately raising and lowering the upper plungers and the lower plungers including a rocker arm connecting the lower plungers and means for alternately feeding material to the two passages, and a single crank shaft with means of connections to the upper plungers for alternately operating the same.

30 12. A molding press comprising a die bed having two die passages, plungers movable above and below each die passage, a feed slide having passages adapted to alternately register with the die passages and a screw feed device located between the upper plungers for feeding material alternately to the passages in said slide.

35 13. In a molding press, a die bed having two passages, plungers mounted above and below said passages, a rocker arm connecting the lower plungers and hydraulic pressure means for cushioning the lower plungers alternately, said lower plungers being raised

alternately by the rocker arm and depressed alternately by the upper plungers.

40 14. A molding press comprising a die bed having a passage, plungers mounted above and below said passages, hydraulic pressure means for cushioning the lower plunger, a crank shaft for operating the upper plunger, a feed slide having a passage for the upper plunger and means for feeding material to the passage in the feed slide when it is out of registry, and means for moving said feed slide and its contained material to a position of registry with the passage in the die bed when the upper plunger is raised and the lower plunger is depressed.

45 15. A molding press comprising a die bed having a passage, a feed slide above said passage, having a passage for material, means for feeding material to the passage in said feed slide, means for varying the amount of material fed to the feed slide, a plunger movable from beneath said die bed into the passage therein, hydraulic pressure means for cushioning said plunger, a plunger movable from above said die bed through the passage in the feed slide and into the passage in the die bed, and a crank shaft for operating the upper plunger.

50 16. In a molding press, a die bed having a recess, a lower molding plunger movable in said recess and formed of at least two parts one of which has an upper molding surface which surrounds and is normally below the upper molding surface of the other part so as to provide room for a greater depth of moldable material around the edges than over the central part, an upper abutment above said recess and means for moving the molding surfaces of the two parts of the lower plunger to bring them to a common level to compress the material in the recess against the lower surface of said abutment, the edges of the material being compressed more than the center.
